UNITED STATES PATENT OFFICE.

THOMAS LITWILLER, OF TREMONT, ILLINOIS.

ENGINE.

SPECIFICATION forming part of Letters Patent No. 623,168, dated April 18, 1899.

Application filed March 26, 1897. Serial No. 629,456. (No model.)

To all whom it may concern.

Be it known that I, THOMAS LITWILLER, a citizen of the United States, residing at Tremont, in the county of Tazewell and State of Illinois, have invented certain new and useful Improvements in Engines; and I do hereby declare that the following is a full, clear, and exact description of the invention, which will enable others skilled in the art to which it appertains to make and use the same.

The object of the present invention is to provide an improved construction of balanced slide-valves by means of which a balance-valve is constructed that is well adapted for the purpose designed.

By means of the construction I employ in carrying out my invention both the combination of valves and the means for connecting and actuating the said valves are very simple and durable and are arranged and manipulated to utilize the motive agent to the greatest advantage and constructed to reduce the friction to a minimum.

The invention consists of certain parts and details and combinations of the same, as will hereinafter be described, and then pointed out in the claims.

Reference is to be had to the accompanying drawings, forming a part of this specification, in which similar letters of reference indicate corresponding parts in all of the figures.

Figure 1 is a plan view of an engine and steam-chest. Fig. 2 is a horizontal section showing the interior of the cylinder and steam-chest and the relative position of the working parts. Fig. 3 is an elevation of the steam-chest with the front wall thereof removed. Fig. 4 is a section on the line X X of Fig. 3.

In the drawings I have shown and described my invention as applied to a multiple-piston engine and will proceed to describe the working function of the same in connection with my balance-valve.

The bed-frame of the engine is as a whole indicated by M.

B is the steam-cylinder, containing the piston-heads N O P and suitably secured on the bed-frame, the ends of which are closed by the heads b⁵ b⁶, secured thereto by set-screws or by other suitable means.

a b are steam-ports opening out of steam-

chest E. The steam is delivered to the cylinder from the steam-chest through the said ports a b and exhausts therefrom through the same ports.

The pistons in cylinder B are adapted to operate in the manner shown, and the said cylinder has its ports a b adapted to register alternately with the ports c d, formed in the main slide-valve D', mounted to slide in the steam-chest E. F is a valve-stem connected with the mechanism for imparting a reciprocating motion to the said valve, consisting of the pitman-bar F', pivoted to the rod and eccentrically carried and driven from shaft V', for imparting a reciprocating motion to said valve to alternately connect the ports c d with the ports a b, respectively.

c' is an exhaust port, space, or opening in the valve D', and c² is an exhaust port or opening cored into the steam-chest E between the ports a and b and adapted to communicate with the exhaust-port c', where it opens out through the bottom face of the main valve D'. Within the steam-chest is located a second or cut-off valve H, seated on the main valve and consisting of a flat lower part and a central raised neck, having a chamber adapted to communicate with the exhaust c', where it opens out at a point in the top face of valve D', and this valve H is adapted to be reciprocated in the steam-chest in such a manner as to alternately open and close the ports c d in valve D', the said valve H being adapted to reciprocate throughout the greater portion of its movement in an opposite direction from the movement of the valve D'. Said valve H is also adapted to have a one-fourth lead over the said valve to facilitate in the proper working of the combined valves and adapted to so operate in connection with ports c d that as one port is opened to admit steam the other will be closed; but the exhaust-ports or one of them at a time will be opened a short time after its matching port has been closed.

H' is a stem connected with valve H, which said stem is pivotally connected with pitman-rod H², which is eccentrically connected with driving-shaft V' in the usual way. The valve H is composed of a lower part provided with an upwardly-projecting rectangular neck that bears in close proximity to the outside wall of the steam-chest, and h h and h' h' are sections

of a loose-jointed ring or frame bearing around the neck and resting against the flat lower part of this valve, where it projects beyond the neck's contour. The two end sections *h h* 5 are provided with notches in their inner faces a short distance from their extremities, which receive the extremities of the two side sections *h' h'*, so as to permit all sections to fit closely around the neck. In said lower part 10 are two upright pins *k k*, spaced just outside the end sections *h*, and *i i* are leaf-springs, each having a depressed center engaged inside one of said pins and two bent ends bearing upon the outer face of its section *h*, 15 whereby the four sections are held together. The sectional frame is held against the side wall of the steam-chest in such manner as to produce a practically steam-tight joint by means of other and similarly-constructed 20 spring *m m'*, whose bent ends bear against the lower edges of the side sections *h'* and whose depressed centers rest one upon a lug *m* at one side of the neck and the other upon the valve-stem *H'*, which is secured to the valve. 25 By forming the valves in the manner shown I am better able to produce a practically complete balanced valve. Of course some little steam may escape into the interior of the valve or into the exhaust-space provided in 30 each, but not enough to in any way affect the principle of working of the valve. In connection with the steam-chest I provide the stuffing-box *n*, which carries the stems *F* and *H'*. The steam enters the steam-chest through 35 the inlet-opening *K* in the top portion thereof. As before mentioned, through the body of the main valve *D* is arranged the exhaust-port *c'*, which also opens into the chamber in valve *H* and connects with the outlet *c²*, leading to 40 the outside, it being understood that the steam passing into the steam-chest from the cylinder can pass through the exhaust-ports to the outside. The valves *D'* and *H* are somewhat less in width than the steam-chest, and hence 45 the valve way or seat is correspondingly less in width, but extends the entire length of the steam-chest, as plainly shown in the drawings. Having thus fully described my invention, 50 what I claim, and desire to secure by Letters Patent, is—

1. In an engine, the combination with the cylinder, piston, steam-chest, and main valve therein having steam and exhaust ports; of the herein-described cut-off valve comprising 55 a flat lower part and an upwardly-extending hollow rectangular neck of smaller contour, means for reciprocating both valves, pins in the lower part of the cut-off valve at opposite ends of and remote from the neck, a frame 60 surrounding the latter and consisting of two end sections notched near their extremities and two side sections whose extremities fit said notches, expansive springs between said pins and the end sections for holding all sections engaged, and expansive springs between 65

said lower part and side sections for holding the latter in contact with the wall of the steam-chest, substantially as described.

2. In an engine, the combination with the steam-chest, and the main valve therein having steam and exhaust ports; of a cut-off valve comprising a flat lower part and an upwardly-extending rectangular neck of smaller contour, means for moving both valves, pins in the lower part of the cut-off valve at opposite 70 ends of and remote from said neck, a frame surrounding the latter and consisting of two end sections notched in their inner faces near their extremities and two side sections whose extremities fit the notches, and a removable 75 leaf-spring between each end section and its adjacent pin, the spring having a depressed center bearing against said pin and bent ends contacting with the outer face of said section to hold its notches engaged with the extremities of the side sections, substantially as described.

3. In an engine, the combination with a steam-chest having parallel cover and seat, and the main valve reciprocating therein and provided with steam and exhaust ports; of a cut-off valve reciprocating between the main valve and cover and comprising a flat lower part and an upwardly-extending rectangular neck, a lug at one end of the latter, a valve-stem connected with the other end thereof, a frame surrounding the neck and consisting of two end sections and notches in their inner faces and two side sections whose extremities engage said notches, means for pressing the end sections inward, and leaf-springs having depressed centers resting on said lug and stem respectively and bent ends for holding the side sections in contact with the wall of the steam-chest, substantially as described. 90

4. In an engine, the combination with the cylinder, the usual steam-chest with its ports and having parallel cover and seat, and the main reciprocating slide-valve having two main ports and an interposed exhaust-port 95 extending through its body; of a cut-off valve upon the main valve and beneath said cover, said valve having a flat lower portion and an upwardly-extending neck provided with a chamber adapted to register with said exhaust-port, a loose-jointed frame surrounding 100 said neck and comprising four sections, two springs for holding said sections engaged with each other, and two other springs for holding certain sections in contact with the cover of the steam-chest and the bodies of the two valves in contact with each other, all substantially as described.

In testimony whereof I affix my signature in presence of two witnesses.

THOMAS LITWILLER.
